HANDWHEEL

Samuel G. Green, Gray, Ga., and Forrest K.
Howard, East Falls Church, Va.

Application January 25, 1935, Serial No. 3,442

5 Claims. (Cl. 116—124)

(Granted under the act of March 3, 1883, as
amended April 30, 1928; 370 O. G. 757)

The invention described herein may be manufactured and used by or for the Government for governmental purposes, without the payment to us of any royalty thereon.

5 This invention relates to a handwheel.

The purpose of the invention is to provide a simple and effective clamp for the dial ring of a handwheel and to provide a retaining member for the ring which forms part of a click latch.

10 To these and other ends, the invention consists in the construction, arrangement and combination of elements described hereinafter and pointed out in the claims forming a part of this specification.

15 A practical embodiment of the invention is illustrated in the accompanying drawing, wherein:

Fig. 1 is a view of a housing containing gearing which is controlled by the improved handwheel.

Fig. 2 is a view in side elevation thereof.

20 Fig. 3 is a sectional view on the line 3—3 of Fig. 2.

Fig. 4 is a detail view in elevation of the retaining plate.

Fig. 5 is a perspective view of the clamping bolt.

25 Referring to the drawing by characters of reference there is shown a housing 5 in which a shaft 6 is mounted on anti-friction bearing units 7—7. A pinion 8 on the shaft has a worm 9 for driving 30 a worm wheel 10.

One end of the shaft 6 projects from the housing and mounts a handwheel 11 which is fixed on the shaft by means of a pin 12. The handwheel is formed with an annular seat 13 for supporting a 35 tapered dial ring 14 which is positioned adjacent the housing. The ring 14 is inscribed with a scale 15 which is readable against an index 16 on the housing.

The ring 14 is retained on its seat by a plate 40 17 which has a beveled edge 18 engaging the tapered interior wall 19 of the ring. The plate is secured to the face of the hub 20 of the handwheel by means of screws 21 and is initially positioned for assembly thereto by means of a pin 22 receivable in an aperture 23 in the hub 20. The outer face of the plate is formed with radially disposed teeth 24 adapted to be engaged by the pointed head of a plunger 25 which is mounted in a thimble 26 inserted in a recess 27 in the housing. The plunger is normally urged into engagement with the plate 17 by a spring 28 housed in the thimble. The assembly constitutes a click latch for the handwheel.

50 The dial ring is arranged to be clamped to the handwheel by means of a bolt 29 which extends

through the handwheel and has a tapered head 30 adapted to engage the tapered interior wall 19 of the dial ring. A portion of the head 30 of the bolt is cut out as at 31 for the purpose of engaging the hub 20 of the handwheel and thereby maintaining the bolt against rotational displacement. The bolt has a bearing surface 32 directly in rear of the head.

5 A nut 33 is mounted on the threaded stem of the bolt and is restrained against axial displacement while being free to rotate by means of a plate 34 which is secured to the handwheel by a pin 35 and has its inner end riding in an annular groove 36 in the nut. As a consequence of this arrangement rotation of the nut causes the bolt to be advanced or retracted to respectively free or clamp the dial ring. When the dial ring is free it may be rotated to adjust the scale 15 with reference to the index 16. When the dial ring is clamped it moves with the handwheel.

20 We claim:

1. A support, an index thereon, a shaft carried by the support and having a projecting end, a handwheel fixed on the projecting end of the shaft and having an annular seat, a ring with a 25 tapered interior wall mounted on the seat and having a scale readable against the index, a plate secured to the handwheel and retaining the ring, said plate having radially disposed teeth on its outer face, a plunger carried by the support and engaging the teeth of the plate, a bolt mounted in the handwheel and having a tapered head arranged to engage the interior wall of the ring, means whereby the bolt is held against rotational displacement, a nut threaded 30 on the bolt, and means for holding the nut against axial displacement.

2. A support, an index thereon, a shaft carried by the support and having a projecting end, a handwheel fixed on the projecting end of the shaft, a ring with a tapered interior wall mounted on and abutting the handwheel, said ring having a scale readable against the index, a bolt mounted in the handwheel and having a 40 tapered head arranged to engage the interior wall 45 of the ring, means whereby the bolt is held against rotational displacement, a nut threaded on the bolt, and means for holding the nut against axial displacement.

3. A support, an index thereon, a shaft carried by the support and having a projecting end, a handwheel fixed on the projecting end of the shaft, a ring with a tapered interior wall mounted on and abutting the handwheel, said ring having a scale readable against the index, a bolt mount- 55

ed in the handwheel and having a tapered head arranged to engage the interior wall of the ring, and means for holding the bolt with its head in clamping engagement with the ring.

5. A support, an index thereon, a shaft carried by the support and having a projecting end, a handwheel fixed on the projecting end of the shaft, a ring with a tapered interior wall mounted on and abutting the handwheel, said ring having a scale readable against the index, and means carried by the handwheel and engaging the interior wall of the ring for clamping the ring to the handwheel.

10 4. A support, an index thereon, a shaft carried by the support and having a projecting end, a handwheel fixed on the projecting end of the shaft, a ring with a tapered interior wall mounted on and abutting the handwheel, said ring having a scale readable against the index, and means carried by the handwheel and engaging the interior wall of the ring for clamping the ring to the handwheel.

5. A support, an index thereon, a shaft carried by the support and having a projecting end, a handwheel fixed on the projecting end of the shaft, a ring with an interior tapered wall mounted on and abutting the handwheel, means 5 for clamping the ring to the handwheel, said ring having a scale readable against the index, a plate secured to the handwheel and retaining the ring, said plate having radially disposed teeth on its outer face, and a plunger carried by the support 10 and engaging the teeth of the plate.

SAMUEL G. GREEN.
FORREST K. HOWARD.
